UNITED STATES PATENT OFFICE.

CLAUD LAY, OF SEALY, TEXAS.

ACETYLENE-GAS GENERATOR.

1,286,665.

Specification of Letters Patent.

Patented Dec. 3, 1918.

Application filed December 29, 1916. Serial No. 139,615.

To all whom it may concern:

Be it known that I, CLAUD LAY, a citizen of the United States, residing at Sealy, in the county of Austin, State of Texas, have invented a new and useful Acetylene-Gas Generator; and I do hereby declare the following to be a full, clear, and exact description of the invention, such as will enable others skilled in the art to which it appertains to make and use the same.

This invention relates to the art of gas generation, and more especially to an improved apparatus for generating acetylene gas.

15 One of the objects of the invention is to provide a gas generating tank provided with a carbid receptacle having improved means for controlling the carbid, in combination with a gas tank provided with a gasometer-bell, the rise and fall of which operates the carbid controlling means, through the medium of improved connections between said bell and said means.

25 A further object of the invention is to provide a carbid receptacle having a conical bottom provided with an opening therein, and a cylindrical valve having diametrically oppositely arranged openings and operating through said central opening to control the carbid in its flow into the water of said gas generating tank.

In practical fields, the details of construction may necessitate alterations falling within the scope of what is claimed.

35 The invention comprises further features and combinations of parts, as hereinafter set forth, shown in the drawings, and claimed.

In the drawings:

40 Figure 1 is a view in side elevation of the improved acetylene gas generator, constructed in accordance with the invention.

Fig. 2 is a plan view.

Fig. 3 is a vertical sectional view on line 3—3 of Fig. 2.

45 Fig. 4 is a cross sectional view on line 4—4 of Fig. 3.

Fig. 5 is a detail view in section on line 5—5 of Fig. 2.

50 Referring more especially to the drawings, 1 designates a tank to contain a suitable amount of water, as shown at 2, and in which gas is to be generated. Constructed integrally with and rising upwardly from the upper part of said tank 1 is a carbid receptacle 3 provided with a substantially coni-

cal bottom 4 having an opening 5. Secured by rivets or the like 6 to the conical bottom, are the arms 7 of the arch piece 8, which depends downwardly from said conical bottom into the interior of the tank 1. A hollow cylindrical valve 9 (having its upper end 10 closed and its lower end 11 open) is mounted to move vertically through the opening 5 of said conical bottom. Extending upwardly from the closed end 10 of said valve 65 is a valve stem 12, which passes through a suitable stuffing box gland 13 in the top of the receptacle 3. One end of a spring 14 is attached at 15 to the under face of the upper end 10 of said valve 9, and has its 70 other end connected at 16 to the arch piece 8. By the action of this spring, the valve 9 may be held down, so that the diametrically oppositely disposed openings 17 will assume positions below the conical bottom 4 of the 75 receptacle 3, thereby cutting off the supply of carbid. However, when the valve is raised to a position substantially as shown in Fig. 3, the carbid will flow through the opening 5 and through the openings 17 into 80 the water of the tank 1. The top of the receptacle 3 is provided with a filling opening 18, which is covered by a suitable cap or closure 19, which may be threaded or otherwise secured in place. Extending from and 85 communicating with the lower part of the tank 1 is a pipe 20, the upper portion of which is held braced by means of the bracket 21. By means of this pipe, the tank 1 may be filled with water. The side of the tank 1 90 is provided with a valve cock 22, which may be opened in order to test whether or not the tank 1 has been filled with water approximately to the amount shown in Fig. 3. A rocking rod 23 is mounted vertically in the 95 tank 1, so that its lower end will engage a bearing 24 in the bottom of the tank 1. An arm 25 is secured on the lower portion of the rod 23 by means of a set screw 26.

The upper portion of the rod 23 terminates 100 in a crank 27 having a handle 28, whereby, upon rocking the rod, the arm 25 may be oscillated, for stirring or agitating the carbid in the water of the tank 1, in order to insure a thorough and complete chemical co-action between the water and the carbid for generating the gas. A gas tank 29 is provided, and secured to the same by means of rivets or the like 30 is an upright member 31 having a right angled extending arm 32 at 110

its upper end. Carried by the tank 29 diametrically opposite the upright 31 is a bracket 33, in a bearing 34 of which a rod 35 is guided. The upper end of the rod 35 has 5 forks 36. Mounted to raise and lower telescopically in the tank 29 is a gasometer bell 37, and threaded in a socket 38 of the top of said bell is a rod 39, which is guided in the arm 32, to guide the bell, and to hold 10 the same concentric with the tank 29. A tube 40 is provided and has its lower end open, and its upper portion merging into an enlargement 41, which is integrally connected to the top of the bell 37. This hollow 15 enlargement 41 is provided with a plurality of perforations or openings 42. A suitable pipe 43 extends from the upper part of the tank 1 downwardly and through the wall of the tank 29, and then upwardly into the said 20 gasometer bell 37, terminating between the top of the gasometer bell and the level of the water in the tank 29. This pipe 43 is provided with a suitable valve 44, which may be arranged or manipulated to 25 govern the gas in its flow or passage from the tank 1 into the gas chamber 45 of said bell. Extending through the wall of the tank 29 and upwardly telescopically into the tube 40 is an outlet pipe 46, its upper end terminating 30 in communication with the enlargement 41. The lower end of the pipe 46 has an annular threaded flange 47, and between this flanged end and an adjacent flanged end 48 of another pipe 49 (which may extend to any 35 suitable source of consumption) a wire fabric strainer 50 is arranged. A sleeve 51 is carried by the flanged end 48, and is in turn threaded to the flange 47, to couple the two pipes 46 and 49 together. A lateral extension 52 is secured by rivets or the like 53 to the top of the gasometer bell 37, and to the extremity of this extension, the rod 35 is attached at 54. A lever 56 is pivoted on the pin 60 between the forks 59 of an 40 upright arm 58, which is secured in any suitable manner to the tank 1. The lever 56 is provided with forks 56^a engaging under where the rod 35 is connected to the arm 52, so that when the bell 37 rises, the same being 45 full of gas, the valve 9 will gradually close incident to the tension of the spring 14. When said bell 37 rises, the arm 52 moves with it, thereby permitting the spring 14 to gradually close the valve 9. However, when 50 the gas is all used from the bell 37, it descends, and when the forks 56^a are again brought in contact with the forks 36 of rod 35, the lever 56 is tilted, thereby causing the valve 9 to rise to an open position and permit the carbid to pass or fall through the 55 openings 17 of the valve and into the water of the generator tank 1. It is to be seen that one end of the lever 56 terminates in forks 61 having slots 62, through which a pivot pin 63 extends, thereby connecting the valve

stem to the lever 56, whereby said lever is allowed freedom of movement to actuate the valve 9 according to the movement of the gasometer bell. However, when the valve 9 is in a raised position, and it is desired to 70 quickly decrease the generation of the gas to a certain degree, a slight manual pressure may be applied to the stem 12, in which case the flow of carbid will be slightly lessened. The gas, when generated in the tank 1, will 75 pass through the pipe 43 into the chamber 45, then into the enlargement 41 and downwardly through the pipe 46, being carried off to some suitable point of consumption, not shown. The gas, in passing off through 80 the pipe 46, very often carries very small particles of the carbid, hence, these are strained from the gas by means of the screen or wire fabric 50. The water in the tank 29 also extends upwardly into the tube 40, 85 thereby providing a suitable fluid seal between the tube 40 and the pipe 46. As the gas increases in the chamber 45, due to the consumption being less than the generation, the gasometer bell rises to a high position in 90 the tank 29, releasing the lever 56 and permitting the valve 9 to lower, thereby causing the openings 17 to assume positions below the conical bottom of the carbid receptacle and closing the opening 5, thus shutting off 95 the flow of carbid and decreasing the generation of gas in the tank 1. As the gas in the chamber 45 lessens or decreases, due to the consumption of the same, the gasometer bell lowers, and through the medium of the lever 100 56, opens the valve 9, thereby permitting the carbid to flow, until again shut off by the raising of the bell. These cycles of operation consecutively repeat.

It will be observed that the enlargement 105 41, with its perforations 42, acts as a preliminary strainer for the gas. This enlargement, being permanently connected with the top of the gasometer bell, necessitates the gas leaving the tank always at the 110 top of the bell, thus reducing the liability of carbid particles entering the pipe 46, since the force of gravity will tend to keep such particles out of the enlargement 41, should they be present in the storage tank.

115 The invention having been set forth, what is claimed as new and useful, is:—

The combination with a gas generating tank, of a carbid receptacle integrally positioned on the top of the tank and provided 120 with a conical bottom protruding into the tank, said conical bottom having a central opening, an arched member fixed to the conical part of the bottom with its transverse part across and spaced downwardly from 125 the opening, a hollow tubular cylindrical shell valve movable vertically in said opening having its lower end open and its upper end closed, a spring interior to the valve and concentrically disposed with reference to the 130

cylindrical surface thereof, said spring being connected between the upper closed end of the valve and the transverse part of the arch member, said valve having an extension 5 guide on its closed end guided in the upper end of the carbide receptacle, a gas storage tank, means connecting the storage tank with the extension guide, whereby the amount of gas in the storage will determine 10 the operation of the valve and the subsequent generation of additional gas, said valve having diametrically disposed openings, whereby the communication between the receptacle and the tank may be closed or 15 opened, the cylindrical wall of the valve below said diametrically disposed openings co-

operating with the marginal edge of the bottom opening, so as to check the lower particles of the carbide in said receptacle, while the wall above said diametrically disposed openings coöperate with the marginal edge of the bottom opening to close the communication between the receptacle and the gas generating tank.

In testimony whereof I have signed my 25 name to this specification in the presence of two subscribing witnesses.

CLAUD LAY.
